UNITED STATES PATENT OFFICE

GEORGE E. DEAN, OF GRAND RAPIDS, MICHIGAN, ASSIGNOR TO CHARLES G. WILLETT,
OF GRAND RAPIDS, MICHIGAN

ROAD GRADER

Application filed January 9, 1931. Serial No. 507,552.

This invention pertains or relates to a mechanism adapted to rotate a revolvably mounted member through a predetermined arc and more particularly to an adjusting device adapted to be applied to the circle or turntable of a road scraper.

Road scrapers are widely used for scraping the road to level or smooth the same or for removing snow and ice therefrom in the winter time and in the type herein set forth the scraper unit is mounted in dependent relation to the side members of a truck.

In the above referred to type of scraper the side members of the truck support depending brackets carrying spaced parallel members, these members supporting the turntable thereon. The turntable has a cross beam rigid therewith and blades are pivotally mounted underneath this cross beam. Hydraulic cylinders are supported by the beam and linkage connects the pistons operating in these cylinders with the pivoted blades whereby power operation of the blades is had. Control of the cylinders is had through a novel system of control as set forth in my application filed January 2, 1931, Serial No. 506,152.

The present invention deals with mechanism for rotating the turntable of scrapers of the class referred to and also to means for automatically rendering the rotating means inoperative after a certain predetermined movement of the turntable has taken place.

One of the principal advantages of my invention lies in the novel arrangement of parts whereby the turning movement of the turntable is utilized in the stopping of the prime movers which motivate the mechanism which drives the turntable.

Another feature which I deem important resides in the double mounting of the worm shaft. This makes for a substantial construction and utilizes the motors not only as prime movers but also makes them serve as bearings when they are not energized.

Still another advantage resides in my adjustable or longitudinal sliding cross bar whereby the same may be slightly shifted endwise in order to change the degree of engagement between the teeth of the pinion and

the toothed segment upon the turntable. Moreover, the slotted end construction of this bar allows it to be attached to parallel side members regardless of their spacing.

Other objects of this invention will be set forth in the following description and drawings which illustrate a preferred embodiment of this invention, it being understood that the above general statement is extended merely to generally explain the same and not to limit it in any manner.

Briefly described, my invention consists of a cross bar located adjacent to the turntable of a road scraper, this bar supporting two aligned motors thereon. The motors have a common shaft extending through a housing supported therebetween and a worm is fixed to the common shaft interiorly of the housing. A vertical stub shaft is mounted in the housing and a worm wheel thereon meshes with the said worm, thus causing rotation of the stub shaft whenever either of the motors is driven. A pinion is mounted upon the stub shaft exteriorly of the housing and engages a toothed segment upon the turntable whereby the turntable and is depending scraper blades are rotated to the desired position. The motors are preferably identical in construction whereby operation of one will cause rotation of the turntable in a direction opposite to that of the other. The motors are electrically driven and a circuit breaker is positioned adjacent the turntable whereby contact is made therewith to prevent excessive movement of the turntable.

Referring to the drawings:

Fig. 1 is a plan view of the under carriage of a truck equipped with my invention.

Fig. 2 is a side view of the scraper attachment illustrated in Fig. 1.

Fig. 3 is a view taken from underneath Fig. 2.

Fig. 4 is a rear view of a turntable equipped with my novel adjusting and locking mechanism.

Fig. 5 is a view taken along the line 5-5 of Fig. 3, and

Fig. 6 is an enlarged plan view showing the details of the circuit breaker.

Similar numerals refer to similar parts through the several views.

Referring particularly to Figs. 1 and 2, 10 indicates the side members of a truck equipped with my invention. These side members 10 support vertically adjustable brackets 11, these brackets supporting spaced parallel bars 12 which in turn carry adjustable shoes 13, these shoes overlapping the turntable 14 and revolubly supporting the same.

The turntable 14 carries a beam 15, from which blades 16 pivotally depend. Hydraulic means 17 are mounted upon either side of the beam 15, this hydraulic mechanism, controlled by the valve arrangement 18, acting to move the blades 16 about the beam 15. The above structure has been fully described and claimed in a copending application previously referred to.

The turntable 14 has a tooth segment 20 rigidly affixed thereto. See Fig. 3. A cross bar 21 is slotted and adjustably connected to the members 12, as indicated at 22, and prime movers or motors 23 and 24 are fastened underneath of the bar and support a housing 25 therebetween.

The housing 25 has a cover member 26 and the motor shaft 27, this motor shaft being common to both motors, passes through opposite sides of the housing. A worm 28 is rigidly mounted on the shaft 27 interiorly of the housing. A stub shaft 29 is vertically mounted in the housing and a worm wheel 30 is rigidly attached thereto and engages with the worm 28. A pinion 31, see Fig. 5, engages with the toothed segment of the turntable 14 and thus rotation of either motor will cause movement of the turntable.

40 The cross bar 21 serves to support the elements or arms 35 and 36 of the circuit breaker, these arms being pivoted as indicated at 37 and 38, respectively. A spring 39 is stretched between the rear portions of the 45 arms and serves to maintain the same against the contact points 40 and 41. These contact points are mounted upon the stationary block 42 respectively connect to the wires 50 and 51, these wires leading to any suitable 50 control mechanism such as the double throw switch 52 and power is supplied by the storage battery 53, this battery preferably being the one used in the truck. Electrical conductors 60 and 61 lead from the rear portions 55 of the arms 36 and 35, respectively, and energize their respective motors. Motors 23 and 24 are grounded as indicated at 63 and 64, respectively.

The turntable 14 has members 65 and 66 60 extending thereacross and these members are adapted to contact with the arms 35 and 36, respectively, whenever the turntable has been rotated its maximum in either direction.

65 The operation is easily understood. When ever the driver of the truck, who is also the

manipulator of the scraping mechanism desires to rotate the turntable in order to place the blade at the chosen angle to the roadway which is being scraped he simply energizes one or the other of the motors by operation of the double throw switch 52, in the proper direction. This manipulation causes one of the motors to operate and thus the shaft 24, worm 28, worm wheel 30, pinion 31 and turntable 14 are actuated, thereby causing the blade to travel toward the desired position.

When the proper position of the blade has been reached, the operator releases or turns the double throw switch to its neutral position, as shown in Fig. 1, and the blade is locked in its adjusted position due to the usual locking action of the worm with its worm wheel. If the switch 52 should be inadvertently operated first the turntable has rotated to a point where the beam and the blade might contact with the rear wheels, the safety mechanism is brought into operation. This safety mechanism, actuated by the members 65 and 66, abuts against the inner ends of the members 35 and 36, respectively, and thus separate the respective arm from its adjacent contact to thereby break the electric circuit and cause the operation of the motor to cease.

It will be noted that the motor 23 operates in such a direction as to cause the turntable to rotate in a counterclockwise direction with reference to Fig. 1. In this case should the rotation be too far, the member 65 will engage the arm 35 and thus stop the operation of the motor 23. However, the double throw switch 52 may now be thrown to its other position and current will flow through the other side on the arm 36 and thus the turntable may be brought back towards its original position. As soon as it starts in this direction the spring 39 causes the arm 35 to again engage its contact 41.

From the above description it will be appreciated that I have invented an extremely practical and sturdy adjusting unit which may be easily and expediently applied to the particular type of road scraping mechanism herein involved and also which has a safety device which limits the movement of the beam and its scraping blade.

Having thus revealed this invention, I claim as new and desire to secure the following combinations and elements or equivalents thereof, by Letters Patent of the United States.

I claim:

1. A road scraper of the character described comprising a frame; a turntable mounted thereon, a cross bar mounted adjacent the turntable, aligned motors mounted upon the cross bar, a housing intermediate the motors, said motors having a common shaft extending through said housing; a worm on said shaft interiorly of the housing, a worm wheel mounted upon the last men-

tioned shaft and meshing with the worm, a pinion mounted on the last mentioned shaft outside of the housing, a segment fixed concentrically to the turntable and toothed so as to mesh with the said pinion, and means for alternately operating the motors in opposite directions whereby the turntable may be operated in different directions.

2. A road scraper as set forth in claim 1 in which the operating means for the motors has a circuit breaker, and means on the turntable adapted to contact with the circuit breaker upon a limited movement of the turntable whereby the operating means is rendered ineffective.

3. A road scraper comprising a frame, a turntable mounted thereon, a cross bar on said frame located adjacent the turntable, two aligned motors having a common shaft mounted upon the cross bar, a worm upon said shaft, a worm wheel driven by the worm, gearing between the worm wheel and the turntable whereby the latter is driven, and means to alternately energize the motors whereby the turntable is driven in the chosen direction.

4. A road scraper as set forth in claim 3 in which means is mounted on the turntable to render the energizing means inoperative at certain predetermined points of movement of the turntable.

5. A road scraping apparatus having a frame, a turntable mounted thereon, two aligned motors mounted upon the frame and adjacent the turntable, said motors being adapted to rotate in opposite directions when energized, and gearing between the motors and the turntable whereby the latter is actuated.

6. A road scraping apparatus as set forth in claim 5 in which means are utilized for supplying the motors with electrical energy and additional means are mounted upon the turntable, said latter means being adapted to render the former means inoperative upon a predetermined movement of the turntable.

7. A road scraper as recited in claim 5 in which the motors have a common shaft.

8. In combination with a road scraper, a turntable mounted thereon, a cross bar adjacent the turntable, two motors upon the cross bar, a common shaft for said motors, control means for operating the motors independently, gearing between the motor shaft and the turntable and means on the turntable adapted to contact with the control means whereby the control means is rendered inoperative.

9. In combination, a turntable, a support adjacent the turntable, two prime movers mounted on said support, and common means between the prime movers and the turntable whereby operation of one prime mover will cause rotation of the turntable in one direction and operation of the other prime mover

will cause rotation of the turn table in the other direction.

10. A combination of elements as recited in claim 9 and also having means on the turntable to render the prime movers inoperative when the turntable has rotated a predetermined distance.

11. In combination, a turntable, a toothed segment rigid therewith, a support adjacent the turntable, two aligned motors upon said support, said motors having a common shaft, and gearing between the aforesaid shaft and the toothed segment whereby the turntable is rotated.

12. A device of the class described in claim 11 but further characterized by the fact that a circuit breaker is in the circuit energizing the aligned motors and that means are mounted upon the turntable adapted to contact with and operate the circuit breaker whereby the motors are rendered inoperative.

13. In combination with a road scraper, a turntable mounted thereon, a toothed segment mounted upon the turntable, adjustable supporting means adjacent the turntable, a cross bar mounted upon the supporting means, and a pinion supported by the cross bar and adapted to mesh with the said toothed segment, said cross bar being movable relative to the toothed segment, whereby the degree of engagement between the segment and the pinion is varied.

14. In combination, a turntable, a support adjacent thereto, two opposed motors upon said support, and common gearing between the opposed motors and the turntable whereby the turntable is driven in either direction.

15. In combination, turntable, a cross bar, two prime movers supported upon said cross bar, and means between the prime movers and the turntable whereby actuation of the prime movers turns the turntable.

16. A road scraper comprising a turntable having a toothed portion thereon, aligned motors adjacent the turntable, means for individually controlling the motors, and gearing between the opposed ends of the motors and the toothed portion of the turntable whereby the turntable may be driven.

17. A device of the class described comprising a frame, a turntable mounted thereon, aligned motors adjacent the frame, said motors having a common shaft, a worm on said shaft, and gearing between said worm and said turntable whereby the turntable is driven.

In testimony whereof I affix my signature.
GEORGE E. DEAN.
